(57) **CLAIM**

The ornamental design for a double plinth furniture leg design, as shown and described.

DESCRIPTION

FIG. 1 is a perspective view.

FIG. 2 is a top plan view.

FIG. 3 is a bottom view.

FIG. 4 is a front elevational view with the rear elevational view being a mirror image thereof; and,

FIG. 5 is a left side elevational view with the right side elevational view being a mirror image thereof.

The broken lines which define the bounds of the claimed design form no part thereof.
